(57) **CLAIM**

The ornamental design for a display screen with animated graphical user interface, as shown and described.

DESCRIPTION

Reproduction 1.1 is a front view of a first image in a sequence of the first embodiment of a display screen with animated graphical user interface;

Reproduction 1.2 is a front view of a second image thereof; Reproduction 1.3 is a front view of a third image thereof; Reproduction 1.4 is a front view of a fourth image thereof; Reproduction 2.1 is a front view of a first image in a sequence of the second embodiment of a display screen with animated graphical user interface;

Reproduction 2.2 is a front view of a second image thereof; Reproduction 2.3 is a front view of a third image thereof; Reproduction 2.4 is a front view of a fourth image thereof; Reproduction 3.1 is a front view of a first image in a sequence of the third embodiment of a display screen with animated graphical user interface;

Reproduction 3.2 is a front view of a second image thereof; Reproduction 3.3 is a front view of a third image thereof; Reproduction 3.4 is a front view of a fourth image thereof; Reproduction 7.1 is a front view of a first image in a sequence of the fourth embodiment of a display screen with animated graphical user interface;

Reproduction 7.2 is a front view of a second image thereof; Reproduction 7.3 is a front view of a third image thereof; Reproduction 7.4 is a front view of a fourth image thereof; Reproduction 8.1 is a front view of a first image in a sequence of the fifth embodiment of a display screen with animated graphical user interface;

Reproduction 8.2 is a front view of a second image thereof; Reproduction 8.3 is a front view of a third image thereof; Reproduction 8.4 is a front view of a fourth image thereof; Reproduction 9.1 is a front view of a first image in a sequence of the sixth embodiment of a display screen with animated graphical user interface;

Reproduction 9.2 is a front view of a second image thereof; (Continued)

Reproduction 9.3 is a front view of a third image thereof; and

Reproduction 9.4 is a front view of a fourth image thereof. The appearance of the display screen with animated graphical user interface sequentially transitions between the images shown in Reproductions 1.1-1.4, 2.1-2.4, 3.1-3.4, 7.1-7.4, 8.1-8.4, and 9.1-9.4.

The process or period in which an image transitions to another image forms no part of the claimed design.

The broken lines depicting an electronic device, display screen, and portions of the graphical user interface, including but not limited to all text and icons, illustrate environmental structure and portions of the article and form no part of the claimed design.
